ABSTRACT OF THE DISCLOSURE

A microwave oscillator device having means for rapid cyclical variation of the operating frequency over the tuning range including dielectric tuning rods disposed off-axis. Upon rotation or angular displacement parallel to the axis of the device the tuning member traverses the maximum and minimum electric field regions in the resonant cavity to result in capacitive tuning of the device.

The present invention relates generally to microwave oscillator devices of the magnetron type having a coaxial resonant cavity disposed externally or internally of the anode resonator system and more particularly to a new and novel tuning structure for such devices.

A well known microwave frequency generator is the crossed-field magnetron device incorporating a central cylindrical cathode encircled by a plurality of anode cavity resonators. An external magnetic field is applied parallel to the axis of the cathode member while an electric field is established transverse thereto between the cathode and anode members. Electrons traverse the interaction region between the cathode and anode in an orbital path and are coupled sequentially to the anode cavity resonators to generate high frequency oscillations in the so-called "π" mode which are then coupled to the load. Such devices have been rendered as either tunable or fixed tuned structures for pulsed or continuous wave operation.

In late years a more efficient magnetron device has been developed which enhances the stability of the generated frequencies. Such devices incorporate a separate annular resonant cavity system coupled coaxially to a conventional anode-cathode interaction system. In one configuration the annular cavity resonator is mounted externally to the anode member while in the so-called inverted configuration the cavity resonator is centrally disposed with respect to the anode-cathode system which results in the provision of increased cathode emission surface area.

Tuning of the coaxial cavity magnetrons has been heretofore accomplished by means of an annular tuning ring member displaced parallel to the tube axis or essentially in the direction of the applied lines of force of the magnetic field. The frequency of the output oscillations is adjusted by moving the tuning ring coaxially in relation to the anode member. Such tuning structures closely resemble a flat doughnut configuration and conventionally such tuning structures, due to the disposition within the cavity, are fabricated of a metallic material. Displacement of the tuning member simultaneously in all quadrants of the annular cavity resonator gives rise to some rather elaborate actuating structures which are both clumsy and expensive. Additionally, spurious oscillation modes are excited within the cavity resonator to resonances created between the tuning member and the outer walls of the outer cavity resonator.

Another development has evolved in the design of microwave oscillators and accompanying systems incorporating the frequency agility concept which involves rapid changing of the operating frequency by continuous-

2

ly rotating a tuning member and selectively correlating such rotations with the pulsing cycles of the high frequency oscillations. With this technique a complete tuning cycle is covered with each rotation of the tuning member. At speeds in the range of 2,000 r.p.m. or higher and a single anode resonator, thirty-three complete tuning cycles every second may be achieved. If the pulse repetition rate and the rotation rate is synchronized a constant output frequency on each pulse will be generated. Variation of the speed of rotation in relation to the pulsing will produce a great number of combinations of output frequencies and with higher rates of speed more than one frequency cycle can occur in the interpulse interval. Furthermore, variation of the pulse repetition rate while maintaining a constant rotation of the tuning member may provide still another large number of combinations of output frequencies. Rotary tuning to achieve frequency agility has achieved importance in the field of electronic countermeasures to prevent analysis of transmitted signals for the purpose of jamming.

A possible solution to the incorporation of frequency agility by cyclic tuning in coaxial cavity magnetron devices would be to oscillate the metallic tuning ring members up and down at a rapid rate by some mechanism such as a hydraulic actuator. The disadvantages in the provision of such a system, particularly when coupled to a highly evacuated electron tube, is immediately evident. The uniform displacement of such tuning ring members will also give rise to some complex mechanical problems and the additional required structure may be prohibitively costly.

Accordingly, it is an object of the present invention to provide means for the rotary tuning of coaxial cavity magnetrons to provide for rapid cyclical variation of the operating frequency over the tuning range.

Still another object of the present invention is the provision of a rotary tuning apparatus which provides for rapid perturbation of the electric fields of a coaxial annular cavity resonator of the external or internal type for crossed field magnetron oscillator devices.

Another object of the present invention is to provide for capacitive tuning of coaxial cavity magnetrons.

The invention broadly stated comprises the incorporation of a tuning member in a coaxial cavity magnetron of the type hereinbefore described with the tuning element coaxially with relation to the axis of the cavity resonator. Rotation of the tuning element at high speeds in a plane transverse to this axial direction will result in the tuning element in one angular position being placed in the low electric field region while a position rotated 90° thereto places the tuning element in the region of the high electric field. In one embodiment envisaged in the practice of the present invention a pair of parallel diametrically opposed elements are provided which when rotated will achieve one complete cycle of the tuning range. Another embodiment of the invention provides for the eccentric disposition of parallel tuning elements simultaneously in the high and low electric field regions in diametrically opposed quadrants of the cavity. Still another embodiment of the invention incorporates a single tuning element pivotally disposed to simultaneously traverse the low and high electric field regions upon rotation or angular displacement to achieve dither tuning.

A feature of the present invention is the provision of a tuning element of a dielectric material having a high dielectric constant and low dielectric losses. Illustratively, such materials as alumina or sapphire are suggested in the practice of the invention. With the employment of the dielectric continuously rotated tuning member capacitive tuning of the coaxial cavity magnetron is achieved.

In addition to the foregoing, other objects, features and advantages will be readily apparent after considera-

tion of the following detailed specification and reference to the accompanying drawings, in which:

FIG. 1 is a vertical cross-sectional view of an illustrative embodiment of the invention;

FIG. 2 is a cut-away exploded view of a portion of the embodiment shown in FIG. 1 as indicated by the general reference numeral A;

FIG. 3 is a diagrammatic view illustrative of the disposition of the electric and magnetic fields in oscillators of the coaxial cavity type;

FIG. 4 is a vertical cross-sectional view of a magnetron oscillator of the integral cavity type incorporating the embodiment of the present invention;

FIG. 5 is a diagrammatic view of an alternative embodiment of the invention; and

FIGS. 6 and 7 are a plan view and cross-sectional view respectively of still another illustrative embodiment of the invention.

Referring to the drawings, the illustrative embodiment shown in FIGS. 1 and 2 comprises a magnetron oscillator 2 having a cylindrical cathode 4 centrally disposed within a cylindrical anode system including a plurality of cavity resonators 6 defined by inwardly disposed vane members 8 secured to cylinder member 10. Magnetic pole piece members 12 and 14 are disposed on opposite sides of the anode system along the central axis of the over-all tube. Substantially C-shaped permanent magnet members 16 are disposed in a position extending at right angles to the surface of the drawing as viewed by the reader. The disposition of the magnet as shown therefore is 90° out of its actual position and is merely illustrated in this manner for the purposes of the specification to include all applicable structure necessary for the operation of the over-all device. The magnet system described will provide lines of force within the anode-cathode interaction region indicated generally by the numeral 18 as well as the external cavity resonator system to be hereinafter described in a direction substantially parallel to the axis of the cathode 4.

The cathode is supported by a cylindrical member 20 secured in the conventional manner to metallic collar 22 insulatedly secured by means of dielectric member 24 to metallic annular member 26 and pole piece 14. Outer terminal member 28 provides for the energizing of a heater (not shown) within the cathode 4 by suitable high voltages. The remainder of the conventional magnetron oscillator structure comprises cooling fins 30 and exhaust tubulation 32 for evacuation of the internal atmosphere, output waveguide section 34 including a conventional transformer section and mounting plate 36 for supporting the tube in a socket arrangement with or without a viscous fluid coolant circulated in the region adjacent the terminal member 28 and the cathode support structure.

An auxiliary annular coaxial output cavity resonator 38 is defined by outer cylindrical wall member 40 and is coupled to certain anode resonators by slots 42 to permit the introduction of microwave oscillations. There thus are two co-planar conductive walls 10 and 40 extending parallel to the axis of the anode system. The dimensions of the cavity resonator 38 are selected to provide resonant frequencies over a predetermined frequency band with the TE₀₁ mode of oscillation preferred in such coaxial cavity magnetrons.

In accordance with the teachings of the invention means are provided for the varying of the resonant frequencies including in this embodiment a nonconductive tuning element 44 having a pair of parallel diametrically opposed members 46 and 48 disposed parallel to the axis of the anode system and the co-planar walls. Support member 50 provides for the disposition of the elements 46 and 48 as well as coupling to the displacing means of the tuning element in the manner to be hereinafter described. A shaft 52 extends the length of the pole piece 12 to communicate with the actuating means indicated generally by the numeral 54 and is supported throughout its length by

bearings 56, 57 and 58. These bearings may be fabricated of the material sold under the trademark "Graphitar" which is suitable for use as a bearing surface within an evacuated envelope. The tuning element is actuated by rapid rotation thereof to achieve rotary tuning and frequency agility in the manner described in co-pending patent application Ser. No. 248,179, filed Dec. 24, 1962 by Robert E. Edwards and assigned to the assignee of the present invention, now abandoned. A relatively small fractional horsepower motor 60 is mounted outside the tube envelope with torque applied by the so-called magnetic coupling method. Hence, motor 60 drives shaft 61 which engages housing 62 mounted substantially concentric with the axis of the over-all tube and supported for rotation by means of bearing 64. The interior of housing 62 comprises a plurality of members of a magnetic material 65 which substantially encircle cylindrical body member 66 and will be referred to as the drive magnet. Another bearing member 68 is disposed at the lower part of housing 62 to support the rotation thereof. The torque of the rotating drive magnet is translated to a follower member 70 secured to the tuning element shaft 52. Follower member 70 is provided with magnetically permeable material to thereby couple magnetically to the drive magnet 65. The tuning element 44 is thereby rotated continuously in any desired direction with the speed of rotation selected to provide the unique features of rotary tuning to cycle the output frequency over the frequency band of operation at exceedingly high rates of speed in the order of several thousand r.p.m.'s and higher in a sawtooth fashion.

In order to provide an indication of the approximate frequency of the magnetron device to set the receiver local oscillator of a system at a predetermined corresponding frequency, a feedback transducer 72 may be provided utilizing a plurality of meshing sets of capacitive plates 74 with the capacitance variation as a function of angular rotation adjusted to resemble the frequency tuning curve of the magnetron. One set of capacitive plates is attached to the tuning shaft 52 while the other set remains stationary. Further details on the feedback transducer arrangement are available in co-pending patent application Ser. No. 428,392, filed Jan. 27, 1965 by Robert E. Edwards and assigned to the assignee of the present invention, now Patent No. 3,379,925 issued Apr. 23, 1968. This arrangement is also claimed in the referenced application and forms no part of the invention as claimed herein.

Referring to FIG. 3 there is shown in diagrammatic form the disposition of the crossed electric and magnetic fields in a coaxial output resonator of the device under consideration operating in the TE₀₁ mode of oscillation. The distribution of the electric fields is indicated by the circular solid lines 76 which traverse the cavity in a plane parallel to the axis of cylinder member 78 while the outer cylindrical member is indicated by the numeral 80. The coupling slots 82 are illustratively shown to provide for the communication of the oscillations generated within the anode-cathode interaction region 84 to the cavity area designated 86. The magnetic lines of force are directed radially in this mode of oscillation and are indicated by the dotted lines 88. We therefore have a cavity defined by planar conductive members 78 and 80 and the point of minimum electric field intensity is in the region adjacent to the respective conductors 78 and 80 while the point of maximum intensity is in the central part of the cavity region. In accordance with the features of the invention the tuning element 44 comprises a nonconductive dielectric rod of a material such as alumina or sapphire having a high dielectric constant and low dielectric losses. The tuning element is rotated through 360° in one quadrant of the over-all cavity 86 to thereby perturb the electric field sequentially through the points of minimum and maximum electric field intensity. With the tuning element disposed in the position indicated by the numeral 44a and the dotted lines the dielectric material is disposed in the region of maximum electric field intensity. A 90° rota-

tion to the position indicated 44b and the solid line places the dielectric tuning elements in the region of the low electric field. As a result an alternation every 90° occurs between the point of minimum and maximum electric field intensity and employment of the nonconductive material results in capacitive tuning of the cavity resonator. This perturbation of the electric field at rapid rates of speed facilitates the cycling of the frequency through the predetermined frequency band and in actual embodiments tuning ranges of between 6 percent to 8 percent have been realized with this tuning arrangement.

In FIG. 4 another magnetron device is illustrated of the type referred to as the inverted oscillator wherein a hollow anode cylinder 90 provides a central coaxial output cavity resonator 91. Extending radially outward from cylinder 90 are a plurality of vane elements 92 to define therebetween anode resonant cavities. One end of cavity 91 is sealed off from the atmosphere by a dielectric window 93 which communicates with the output waveguide 94 to enable the microwave oscillations from the magnetron structure to be coupled out to a utilization load. Magnetic pole piece members 95 and 96 encircle the anode cylinder 90 and concentric insulating discs 97 and 98 are provided at the outer ends to vacuum seal the over-all device. A cathode support member 99 is disposed between the inner ends of pole pieces 95 and 96 with the emissive cathode 100 mounted adjacent the anode resonators to provide an enlarged emissive area. Slots 101 couple the anode resonators to the central internal output cavity resonator 91. In this embodiment the over-all height of the cavity resonator 91 is an integral number of one-half wavelengths long to provide essentially a full wavelength cavity or greater. Slots 101, therefore, alternately couple to one-half of the internal cavity in the manner shown with the slots disposed adjacent to the top and bottom walls of the cavity resonator. In this configuration a support member 102 is sealed at one end of the anode cylinder 90 and it is through this member that the tuning means may be introduced through a passageway suitably vacuum sealed at the outer end.

The tuning element 103 is positioned eccentrically or adjacent to the walls of cylinder 90 and is in turn as in the previous illustration connected by means of shaft 104 to the motor actuating means and magnetic coupling arrangement. Tuning element 103 comprises dielectric rods disposed parallel to the axis of the cylinder and is adapted for rotation in a plane extending normal to the cylinder axis parallel to the disposition of the electric fields within the cavity resonator. Further details relative to the construction of the embodiment shown may be had by reference to co-pending application Ser. No. 387,572, filed Aug. 5, 1964 by Edward T. Downing et al. and assigned to the assignee of the present invention, now Patent No. 3,289,036 issued Nov. 29, 1966.

Referring to FIG. 5, another method of capacitively tuning a coaxial cavity resonator is shown by means of an explanatory diagram. In this alternative embodiment the nonconductive tuning element 105 is pivotally supported by suitable means 106 and adapted to be angularly displaced by means of push-pull rod 107 within cavity 108 fabricated in a manner similar to the configuration shown in FIGS. 1 and 2 with the vane members 109 and slots 110. In this embodiment the method of dither tuning may be practiced by positioning the nonconductive tuning elements initially in the position of the lowest electric field intensity and then displacing same a small angular distance to the position indicated by the dotted line and numeral 105a to the position of the maximum electric field intensity. Lateral displacement of the rod 107 will provide the relatively small tuning range required in this method of tuning which achieves approximately 1/10 of 1 percent of the over-all frequency band.

Still another alternative embodiment is illustrated in FIGS. 6 and 7 comprising eccentric disposition of nonconductive tuning elements in diametrically opposed

quadrants of an output coaxial cavity resonator 120 coupled by slots 111 to the anode-cathode interaction region indicated generally by the numeral 112. The output cavity resonator illustrated is of the external cavity type defined between concentric annular members 113 and 114 to provide the planar parallel conductive surfaces. In the quadrant indicated by the numeral 120A tuning element 115 is in the position of the minimum electric field intensity and simultaneously element 116 within quadrant 120B is also in the similar low intensity electric field region. A circle of rotation revolving about an axis indicated at 117 or eccentrically disposed with respect to the axis 118 of the inner anode cylinder 113 results in the displacement every 90° of the tuning elements to the position of higher field intensity indicated for the purposes of this illustration as 115a and 116a. Another method of practicing the invention is therefore disclosed to provide for perturbation of the electric field of a coaxial cavity magnetron.

While several alternative embodiments have been illustrated and described herein it will be evident to those skilled in the art that a single element tuning member may be rotated through the maximum and minimum electric field regions as well as being laterally displaced as shown in FIG. 5. Further, the high speed frequency agility offered by the rotary tuning means employing a nonconductive element has thus provided an effective oscillator device with means for cycling of the resonant output frequencies over the band coincidentally with the pulse repetition rate. By means of altering the speed of rotation many multiple output frequency signals may be generated for random operation to prevent jamming of use in other countermeasure applications. Additionally, cavity resonators may be capacitively tuned where other modes of oscillation are generated by perturbing the electric field with suitable nonconductive elements disposed in the most suitable manner to traverse the maxima and minima electric field intensity points sequentially in a complete rotational cycle in a plane designed to accomplish this traversal.

What is claimed is:

1. A microwave magnetron oscillator comprising:
a cathode member;
a cylindrical anode member defining a plurality of radially disposed cavity resonators disposed adjacent to said cathode member;
transverse electric and magnetic fields;
an auxiliary annular output cavity resonator disposed coaxially with respect to said anode member;
means for coupling microwave oscillations from said anode cavity resonators to said auxiliary output cavity resonator;
means for capacitively tuning the resonant frequency of said auxiliary output cavity resonator including a nonconductive tuning element disposed within said resonator so as to intersect the maximum and minimum region of electric field intensity;
and means for displacing said tuning elements in a direction normal to the axis of said anode member.
2. A microwave magnetron oscillator according to claim 1 wherein said auxiliary output cavity resonator is disposed externally with respect to said cathode and anode members.
3. A microwave magnetron oscillator according to claim 1 wherein said auxiliary output cavity resonator is centrally disposed within said anode member.
4. A microwave oscillator according to claim 1 wherein said tuning element comprises parallel diametrically disposed rod members of a dielectric material rotatably mounted within said output resonator.
5. A microwave oscillator according to claim 1 wherein said tuning element comprises a dielectric member pivotally disposed within said output resonator and adapted to be angularly displaced from an initial position parallel to the axis of said anode member to result in incremental

variations of the resonant frequency of said output resonator over a predetermined frequency band.

6. A microwave oscillator according to claim 1 wherein said annular auxiliary output cavity resonator comprises spaced parallel planar conductive walls mounted externally with respect to said cathode member and anode resonators and said tuning element comprises a dielectric member disposed parallel to said walls within one quadrant of said resonator and a similarly disposed member is positioned in the diametrically opposed quadrant of said resonator.
